PROCESS FOR SOLVENT EXTRACTION OF OILS

Filed April 10, 1934

UNITED STATES PATENT OFFICE

2,100,429

PROCESS FOR SOLVENT EXTRACTION OF
OILSUlric B. Bray, Palos Verdes Estates, Calif., as-
signor to Union Oil Company of California, Los
Angeles, Calif., a corporation of California

Application April 10, 1934, Serial No. 719,910

11 Claims. (Cl. 196—13)

This invention relates to the extraction of oils by employing a selective solvent. Although applicable to the treatment of other oils, it refers more particularly to the production of lubricating oil by a selective solvent extraction process.

It has been found that desirable paraffinic hydrocarbons can be separated from the undesirable olefinic, naphthenic and/or aromatic compounds by the use of solvents which selectively dissolve the undesirable hydrocarbons but which exhibit only a very limited solvent power upon the desirable paraffinic hydrocarbons.

When I use the term "paraffinic hydrocarbons" I mean those highly saturated compounds which are present in petroleum and which are characterized by a low temperature viscosity susceptibility, i. e. they exhibit a minimum change in viscosity for a given change in temperature. They also are characterized by relative stability to air and sunlight, exhibiting little tendency toward discoloration or sludge formation. This definition is not meant to include those compounds which are usually solid or semi-solid at ordinary temperatures and which are known as "wax" or "petrolatum"; but, of course, it is obvious that my invention is meant to also include the selective extraction of waxy oils. As a matter of convenience hereafter, I will refer to the undesirable components, such as olefinic, naphthenic and/or aromatic hydrocarbons, as the "non-paraffinic" components of petroleum. These fractions are characterized by a relatively high temperature viscosity susceptibility and are relatively unstable to air and sunlight, exhibiting discoloration and sludge formation.

A further indication of the purity of a lubricating oil is its viscosity gravity constant. This constant represents the paraffinicity or naphthenicity of an oil. A high value represents a high degree of naphthenicity while low values indicate relatively greater paraffinicity. Lubricating oils from natural crudes range from 0.903 viscosity gravity constant for an extreme Gulf Coast type to 0.807 for an extreme Pennsylvania type or even beyond. The viscosity gravity constants referred to in this application have been determined by the method employed by Hill and Coates as set forth in the Journal of Industrial and Engineering Chemistry, vol. 20, page 641 of 1928. The "paraffinic" hydrocarbons to which I refer hereinafter are characterized by relatively low viscosity gravity constant, while the "non-paraffinic" constituents of petroleum are characterized by relatively high viscosity gravity constant.

A number of selective solvents for extraction have been found; for example, it has been shown that such materials as aniline, chloraniline, nitrobenzene, dichlorethyl ether, phenol, chlorophenol, cresol, sulphur dioxide commingled with benzene, and furfural are highly selective as solvents for the non-paraffinic hydrocarbons. When these solvents are commingled with petroleum or petroleum fractions under the proper conditions of temperature, the undesirable non-paraffinic hydrocarbons pass into solution to a greater or less extent but a substantial proportion of the desirable paraffinic hydrocarbons remains undissolved. The solution of undesirable hydrocarbons and solvent settles to the bottom of the container and forms an extract phase when relatively heavy solvents are employed. The relatively light paraffinic hydrocarbons rise to the top of the vessel and form a raffinate phase. These phases are then readily separable by ordinary decantation means. The raffinate phase is usually found to contain a small quantity of the selective solvent and the extract phase ordinarily contains a relatively large quantity of the solvent. These fractions may be purified by distillation whereby the solvent is distilled away from the hydrocarbon oils.

In the usual solvent extraction of mineral oil with selective solvents, such as those above mentioned, the separation is not complete. Particularly, all of the paraffinic hydrocarbons, i. e. the more valuable lubricants, are not obtained in the raffinate phase but instead some of the high grade paraffinic oil fractions are found in the extract phase. Due to the similarity of the various hydrocarbon components of mineral oil fractions, such as lubricating oils, the solubility of the undesirable non-paraffinic fractions and the desirable paraffinic fractions in a selective solvent usually differ only in degree and there is, therefore, a tendency for desirable high grade paraffinic oils to be carried away with the extract resulting in a loss in the yield of paraffinic fractions obtained. In other words, in a phase separation of extract and raffinate fractions from mineral oil by employing a selective solvent, an equilibrium of paraffinic components and non-paraffinic components is established between the phases. Consequently some of the desirable paraffinic fractions are found in the extract instead of in the raffinate.

The solubility of oils of relatively high paraffinicity in the extract phase can be reduced by the presence of an anti-solvent with the oil during extraction with a selective solvent. An anti-

- solvent may be defined as a material which tends to prevent the solution of those hydrocarbon fractions which, except for the presence of the anti-solvent, would be dissolved in the extract phase upon extraction of the oil with a selective solvent. When, during extraction, an anti-solvent is introduced into that zone wherein some of the oil of relatively high paraffinicinity is dissolved in the solvent, this valuable oil is rejected from solution and is recovered in the raffinate phase. When, before extraction, an anti-solvent is commingled with the oil to be extracted, the solution of oil of relatively high paraffinicinity in the extract phase is inhibited.
- 15 It is an object of this invention to extract oil with a solvent in the presence of an anti-solvent to force into the raffinate phase that portion desired in the raffinate which would otherwise remain in the extract phase.
- 20 The anti-solvent which I may employ is preferably one which is adapted to form a two phase system with the raffinate produced by the extraction and is soluble in the extract phase. As an anti-solvent having these characteristics, I may employ liquid ammonia, or even water may be used as an anti-solvent when the water forms a solution with the selective solvent with which it is employed.

Under certain conditions, the anti-solvent may be a substance which is a selective solvent when employed alone. For instance, the anti-solvent may be a selective solvent which has less solvent power than the selective solvent employed in the extraction. As an example, the extraction may be accomplished by a selective solvent such as chloraniline or a mixture of liquid sulphur dioxide and benzene, characterized by high solvent power for higher grade material. The anti-solvent which I may use may be liquid sulphur dioxide or other solvent having relatively less solvent power for the higher grade material.

When oil is countercurrently extracted with a selective solvent and when an anti-solvent of the type defined above is commingled with the oil prior to extraction or is introduced into that zone of the extraction into which fresh oil to be extracted is also introduced, I have found that the anti-solvent tends to diffuse through the solvent, being soluble therein, in such manner that the proportion of anti-solvent to solvent decreases between the point of introduction of the anti-solvent and the point of removal of the raffinate from the extraction. If, for instance, the solvent is introduced into the top of an extraction column and the oil and anti-solvent are introduced together in the bottom, the top portion of the column contains solvent of relatively high solvent power whereby an extract phase is produced therein comprising some fractions of relatively high paraffinicinity. As the extract phase descends through the column, it contacts with anti-solvent which is present in successively increasing proportions whereby the oil of relatively high paraffinicinity is rejected from the extract phase and travels upwardly for recovery with the final raffinate.

It is a further object of my invention to countercurrently extract oil with a selective solvent and to introduce into that zone of the countercurrent extraction to which oil entering said extraction is introduced an anti-solvent adapted to form a two phase system with the raffinate and to be soluble in the extract phase whereby the extraction is accomplished by a selective solvent of successively decreasing solvent activity.

Another type of anti-solvent is one which is substantially soluble in the raffinate phase. Anti-solvents having this characteristic are, for example, liquid, normally gaseous hydrocarbons such as liquid ethane, propane, or butane, methyl cellosolve (mono-methyl ether of ethylene glycol), carbitol (mono-ethyl ether of di-ethylene glycol) and other oxygenated compounds such as acetone or methyl acetate. Anti-solvents of this type may be employed if desired, together with the previously mentioned anti-solvents which are adapted to form a two phase system with the raffinate produced by the extraction and which are soluble in the extract phase.

The figure is a schematic arrangement of one form of apparatus which may be employed to carry out my process.

Referring to the figure, oil enters extractor 10 by action of pump 11 in line 12 controlled by valve 13. The anti-solvent which forms a two phase system with the raffinate produced by the extraction and which is soluble in the extract phase, passes by action of pump 14 through line 15 controlled by valve 16 into line 12 to commingle with the oil travelling therethrough. Preferably, the oil and anti-solvent are introduced into the lower portion of extractor 10 for countercurrent extraction with selective solvent introduced into the upper portion thereof by action of pump 17 in line 18 controlled by valve 19. Finished raffinate is removed from extractor 10 via line 20 controlled by valve 21. Extract phase is removed from extractor 10 by action of pump 22 in line 23 controlled by valve 24.

If desired, the extract phase passing through line 23 may enter separator 27 to commingle therein with an anti-solvent introduced by action of pump 28 through line 29 controlled by valve 30. The anti-solvent which enters via line 29 is preferably one which is substantially soluble in the raffinate phase. Accordingly, an intermediate raffinate is rejected from the extract phase in 27. Extract phase is removed from separator 27 via line 31 controlled by valve 32.

When the extract phase from extractor 10 is commingled with an anti-solvent in separator 27 the solution of rejected intermediate raffinate and anti-solvent issues from 27 by action of pump 33 in line 34 controlled by valve 35. This mixture can be introduced into line 12 to commingle with fresh oil brought to extractor 10 when valves 36 and 37 are open in line 34 and valves 38 and 39 are closed in lines 40 and 41, respectively. In some cases it may be desired to introduce this solution into extractor 10 without commingling with fresh oil introduced therein. In this event, the solution may pass through line 34, valves 35 and 36 and valve 39 and line 41, valves 37 and 38 being closed. When it is desired to remove anti-solvent associated with the rejected intermediate raffinate passing through line 34, valve 36 may be closed in order to cause the mixture to pass via line 40 and valve 38 into heater 42 and thence through line 43 into separator 44 wherein the anti-solvent vapors are removed by passage through line 45 controlled by valve 46. The rejected intermediate raffinate freed from anti-solvent then passes by action of pump 47 through line 48 controlled by valve 49 into cooler 50 and thence may travel either through line 41 into extractor 10 or through valve 37 to commingle with fresh oil passing through 12.

As one example of the operation of the above described apparatus, oil characterized by a viscosity gravity constant of 0.875 may be intro-

duced into extractor 10 via line 12 together with 10 volume percent. of water introduced via lines 15 and 12. The oil may be extracted with 200 volume percent. ortho-chlorophenol introduced 5 via line 18. The raffinate issuing via line 20 is characterized by a viscosity gravity constant of 0.810 and is obtained in 40% yield. When the same oil is extracted under the same conditions with ortho-chlorophenol in the absence of the 10 anti-solvent, the raffinate issuing through 20 has about the same viscosity gravity constant but the yield is only 28%, indicating that the anti-solvent reduces the loss of fractions of relatively high paraffinicinity in the extract phase.

15 By introducing the water either commingled with the oil entering the extraction or by introduction of the water into the same zone in which the fresh oil enters the extractor, the proportion of anti-solvent to solvent is greatest at approximately 20 that point at which the fresh oil is introduced. As previously stated, this anti-solvent is soluble in the extract phase and due to the 25 counterflow of materials and to the agitation in extractor 10, the anti-solvent tends to diffuse through at least a portion of the extractor and to be present in successively decreasing amounts as the oil ascends the column. Consequently, the 30 solvent in the upper portion of the column may be substantially unmodified by anti-solvent, and due to the high solvent action of this solvent the extract phase will comprise some fractions of relatively high paraffinicinity desired in the raffinate phase. This extract phase descends through the column and passes through zones of increasingly 35 larger proportions of anti-solvent whereby the solvent power of the selective solvent is successively decreased in the column and the fractions of relatively high paraffinicinity are rejected from the extract phase for recovery in the raffinate 40 passing through line 20.

If desired, both types of anti-solvent may be introduced with the oil entering through line 12, e. g. the oil may be commingled with an anti-solvent such as liquid propane to the extent of 45 400 volume percent. and with water or anhydrous liquid ammonia or the like, to the extent of 12 volume percent. In this case the solvent, such as ammonia, which is adapted to form a two phase 50 system with the raffinate and which is soluble in the extract phase functions in the above described manner for passage of the extract phase through zones of increasing proportion of anti-solvent. While the other type of solvent, e. g. liquid propane, which is substantially soluble in 55 the raffinate phase travels upwardly through column 10 and is discharged with the raffinate.

As another example, oil characterized by a viscosity gravity constant of 0.872 intermixed with 300 volume percent. liquid sulphur dioxide, enters 60 extractor 10 via line 12 for countercurrent extraction with 250 volume percent. of a solvent comprising 70 volume percent. liquid sulphur dioxide and 30 volume percent. benzene. The raffinate issuing through line 20 is characterized by a viscosity 65 gravity constant of 0.808. The extract phase issuing through line 23 having a viscosity gravity constant of 0.890 is introduced into separator 27 for intermixture with liquid propane to the extent of 400 volume percent., based upon the 70 volume of oil introduced into the system via line 12. The material passing through line 34 comprises a solution of liquid propane and intermediate raffinate rejected from the extract phase in separator 27. This mixture is passed by line 75 34 into line 12 for further extraction in extractor

10. Extract removed via line 31 has a viscosity gravity constant of 0.941. The presence of liquid sulphur dioxide introduced by line 12 into extractor 10 causes the extract phase produced by countercurrent extraction with the mixture of 5 liquid sulphur dioxide and benzol to descend through zones of relatively increasing proportions of liquid sulphur dioxide in relation to the benzol whereby the activity of the solvent is successively reduced causing rejection of fractions of relatively high paraffinicinity from the extract phase as the extract proceeds from the upper to the lower portion of extractor 10. The liquid propane introduced through line 29 and passing with the rejected intermediate raffinate through line 34 15 travels upwardly through extractor 10 and issues therefrom with the raffinate via line 20.

As previously stated, when an intermediate raffinate is rejected from the extract phase by means of an anti-solvent soluble in the rejected 20 intermediate raffinate, the solution of rejected intermediate raffinate and anti-solvent passing through line 34 may be commingled with fresh feed and anti-solvent passing through line 12 or it may be introduced into the extraction without 25 first mixing with the fresh feed of oil, for instance, by passage through line 41. Also, the anti-solvent can be removed from the rejected intermediate raffinate by distillation or the like 30 before the rejected intermediate raffinate is returned to the extraction.

It is to be understood that the foregoing is merely illustrative of the generic invention and that the examples are not to be taken as limiting thereof as many modifications of my invention 35 may be made within the scope of the following claims.

I claim:

1. A process for the solvent extraction of oil by a selective solvent into an extract phase comprising oil dissolved in said solvent and a raffinate phase substantially insoluble in said solvent which comprises commingling with the oil to be extracted an anti-solvent soluble in said extract phase and adapted to form a two phase system with the raffinate and countercurrently extracting said mixture with said selective solvent, separating extract phase from raffinate phase and rejecting an intermediate raffinate from said extract phase by commingling said extract phase 40 with an anti-solvent substantially soluble in said rejected intermediate raffinate.

2. A process for the solvent extraction of oil by a selective solvent into an extract phase comprising oil dissolved in said solvent and a raffinate phase substantially insoluble in said solvent which comprises commingling with the oil to be extracted an anti-solvent which is soluble in said extract phase and adapted to form a two phase system with the raffinate, countercurrently extracting said mixture in an extraction system with said selective solvent, separating extract phase from raffinate phase, commingling said extract phase with an anti-solvent to reject an intermediate raffinate therefrom and returning said rejected intermediate raffinate to said extraction.

3. A process for the solvent extraction of oil by a selective solvent into an extract phase comprising oil dissolved in said solvent and a raffinate phase substantially insoluble in said solvent which comprises commingling with the oil to be extracted an anti-solvent which is soluble in said extract phase and adapted to form a two phase system with the raffinate, countercur- 70

rently extracting said mixture in an extraction system with said selective solvent, separating extract phase from raffinate phase, rejecting an intermediate raffinate from said extract phase by 5 commingling said extract phase with an anti-solvent and commingling said rejected intermediate raffinate with fresh oil being introduced into said extraction system.

4. A process for the solvent extraction of oil by 10 a selective solvent into an extract phase comprising oil dissolved in said solvent and a raffinate phase substantially insoluble in said solvent which comprises commingling with the oil to be extracted an anti-solvent which is soluble in said extract phase and adapted to form a two phase system with the raffinate, countercurrently extracting said mixture in an extraction system with said selective solvent, separating extract phase from raffinate phase, rejecting an intermediate raffinate from said extract phase by 15 commingling said extract phase with an anti-solvent substantially soluble in said rejected intermediate raffinate and returning said rejected intermediate raffinate into said extraction.

5. A process for the solvent extraction of oil by a selective solvent into an extract phase comprising oil dissolved in said solvent and a raffinate phase substantially insoluble in said solvent which comprises commingling with the oil to be extracted an anti-solvent soluble in said extract phase and adapted to form a two phase system with the raffinate, countercurrently extracting said mixture in an extraction system with said selective solvent, separating extract phase from raffinate phase, rejecting an intermediate raffinate from said extract phase by 20 commingling said extract phase with an anti-solvent substantially soluble in said rejected intermediate raffinate and commingling said rejected intermediate raffinate with fresh oil being introduced into said extraction.

6. A process for the solvent extraction of oil by a selective solvent into an extract phase comprising oil dissolved in said solvent and a raffinate phase substantially insoluble in said solvent which comprises commingling with the oil to be extracted an anti-solvent soluble in said extract phase and adapted to form a two phase system with the raffinate, also commingling said oil to be extracted with an anti-solvent substantially soluble in said raffinate phase and extracting said mixture with said selective solvent.

7. A process for the solvent extraction of oil by a selective solvent into an extract phase comprising oil dissolved in said solvent and a raffinate phase substantially insoluble in said solvent which comprises commingling with the oil to be extracted an anti-solvent which is soluble in said extract phase and adapted to form a two phase system with the raffinate, countercurrently extracting said mixture in an extraction system with said selective solvent, separating extract phase from raffinate phase, rejecting an intermediate raffinate from said extract phase by 25 commingling said extract phase with an anti-solvent substantially soluble in said rejected intermediate raffinate, removing said anti-solvent from said rejected intermediate raffinate and introducing said rejected intermediate raffinate into said extraction.

8. A process for the solvent extraction of oil by a selective solvent into an extract phase comprising oil dissolved in said solvent and a raffinate phase substantially insoluble in said solvent which comprises commingling with the oil to be extracted an anti-solvent which is soluble in said extract phase and adapted to form a two phase system with the raffinate, countercurrently extracting said mixture in an extraction system with said selective solvent, separating extract phase from raffinate phase, rejecting an intermediate raffinate from said extract phase by 30 commingling said extract phase with an anti-solvent substantially soluble in said rejected intermediate raffinate, heating said solution of anti-solvent and rejected intermediate raffinate to vaporize the anti-solvent, cooling the intermediate raffinate freed from anti-solvent and introducing said rejected intermediate raffinate into said extraction.

9. A process for the solvent extraction of oil by a selective solvent into an extract phase comprising oil dissolved in said solvent and a raffinate phase substantially insoluble in said solvent which comprises commingling with the oil to be extracted an anti-solvent which is soluble in said extract phase and adapted to form a two phase system with the raffinate, countercurrently extracting said mixture in an extraction system with said selective solvent, separating extract phase from raffinate phase, rejecting an intermediate raffinate from said extract phase by commingling said extract phase with an anti-solvent substantially soluble in said rejected intermediate raffinate, removing anti-solvent from said rejected intermediate raffinate and commingling said rejected intermediate raffinate freed from anti-solvent with fresh oil being introduced into said extraction system.

10. A process for the separation of oil containing paraffinic and non-paraffinic constituents into fractions relatively more paraffinic and fractions relatively less paraffinic than the original oil which comprises, commingling said oil with a selective solvent for the relatively less paraffinic oil fractions and thereby forming a raffinate phase containing the relatively more paraffinic oil fractions and an extract phase containing the relatively less paraffinic oil fractions dissolved in the selective solvent, separating said phases, contacting the extract phase with a liquefied normally gaseous hydrocarbon and thereby dissolving the relatively more paraffinic oil fractions present in the extract phase, separating the liquefied normally gaseous hydrocarbon solution of the relatively more paraffinic oil fractions from the remaining extract phase, removing substantially all of the liquefied normally gaseous hydrocarbon from the oil fractions recovered from the extract phase and returning said oil fractions recovered from said extract phase to the oil feed entering the extraction system.

11. A process according to claim 10 in which the liquefied normally gaseous hydrocarbon is liquid propane.

ULRIC B. BRAY.
